UNITED STATES PATENT OFFICE

ARTHUR J. BAKER, OF TOLEDO, OHIO, ASSIGNOR TO THE WILLYS-OVERLAND COMPANY,
OF TOLEDO, OHIO, A CORPORATION OF OHIO

DESIGN FOR A VEHICLE BUMPER

Application filed December 30, 1932. Serial No. 46,659. Term of patent 14 years.

To all whom it may concern:

Be it known that I, ARTHUR J. BAKER, a citizen of the United States, residing in the city of Toledo, county of Lucas and State of Ohio, have invented a new, original, and ornamental Design for a Vehicle Bumper, of which the following is a specification, reference being had to the accompanying drawing, forming part thereof.

In the drawing, Figure 1 is a front view of the vehicle bumper showing my new design;

Figure 2 is a top plan view of the vehicle bumper shown in Figure 1.

My design is particularly characterized by its downwardly and outwardly curved configuration.

I claim:

The ornamental design for a vehicle bumper substantially as shown and described.

In testimony whereof, I affix my signature, this 27th day of December, 1932.

ARTHUR J. BAKER.
